LOCK.

1,368,409.

Specification of Letters Patent. Patented Feb. 15, 1921.

Application filed December 2, 1913. Serial No. 804,215.

To all whom it may concern:

Be it known that I, ALBERT A. PAGE, a citizen of the United States, residing in the town of East Haven, county of New Haven, 5 and State of Connecticut, have invented certain new and useful Improvements in Locks, of which the following is a full, clear, and exact description.

This invention relates to locks, and more particularly to latch bolt locks for school-houses and similar buildings, having means whereby the latch bolt may be held back in the case when retracted by the key. In an application filed July 20, 1912, Serial No. 15 710,570, resulting in the grant of Letters Patent No. 1,126,560, January 26, 1915, I have described a lock having mechanism operable by a key for retracting the latch bolt, and holding it in retracted position, 20 which mechanism was primarily devised for the convenience of the janitor of the building, so that he could readily stop back the latch. When it was merely desired to unlock the door temporarily, the janitor could, by 25 a reverse movement of the key, readily release the latch, after it had been locked in retracted position as a necessary result of its retraction. Certain doors of the building, however, are in use by the teachers, and in 30 entering such doors, the teacher often omits to give the key the necessary movement to release the retracted latch, whereby the doors are frequently left unlocked at times when they should be locked against intrusion from 35 the outside. Moreover, it has been found desirable to prevent the stopping back of the latch from the outside of the door, and confine this function to mechanism operable from the inside of the door, though permitting 40 retraction of the latch from either side.

The primary objects of the present invention are to meet the above conditions; to provide a latch bolt lock having a bolt, retractable by a key or keys inserted at each 45 side of the door, mechanism being provided for stopping back the latch when it is retracted from one side without stopping it back when it is retracted from the other side; to provide a lock having a key for re- 50 tracting the latch bolt, and holding it re- tracted, and another key which will retract the latch bolt, but which will not hold it in retracted position; and to improve the general construction and operation of locks of 55 the class to which my invention relates.

To these and other ends the invention con-

sists in the novel features and combinations of parts to be hereinafter described and claimed.

In the accompanying drawings, 60

Figure 1 is an elevation of a lock embodying my improvements, with the cap plate removed;

Fig. 2 shows the upper portion of the lock with the latch bolt retracted by the key from 65 the outside, the main detent lever being shown in dotted lines;

Fig. 3 is a view similar to Fig. 2, showing the latch bolt retracted by a key from the 70 inside;

Fig. 4 is a reverse view of Fig. 3;

Fig. 5 is a section through the complete lock, on a line corresponding to line 5—5 of Fig. 1;

Fig. 6 is a detail of the main detent lever; 75 and

Fig. 7 is a detail of the keys.

Referring to the drawings, the case 10 of the lock, having the face plate 11, contains a latch bolt 12, normally projected by a 80 spring 13. The stem 14 of the latch bolt carries a head 15, engaged by a lever 16, adapted to be operated by a lifter 17, which is in turn actuated by an inside thumb piece, push bar, or other mechanism (not shown). 85 The particular means for retracting the latch bolt manually from the inside of the door is immaterial. In the particular lock selected for illustration, the retraction of the bolt from the outside of the door is confined to the key, but this is likewise an im- 90 material feature.

The means for retracting the latch bolt, by means of a key, comprises a latch bolt retracting lever 20, pivoted in the case at 21, 95 and having one extremity thereof engaged with the crosshead 15 of the bolt. The re- tracting lever 20 is provided with a projec- 100 tion 23 engaged by an arm 24 of a main detent lever 25, pivoted in the case at 26. The extremity 24^a of the arm 24 extends transversely across the case in operative re- 105 lation to the bit or dog 27 of a cylinder lock 28, inserted in a suitable opening in the case at the inside of the door. When the dog 27 is rotated in an anti-clockwise direction with respect to Fig. 3, said dog will engage the extremity 24^a of the lever 25, thereby mov- 110 ing the arm 24 to the right. This arm, by engaging the projection 23, carries with it in its movement the retracting lever 20, whereby the latch bolt is retracted. A cyl-

inder lock 29, secured in an opening in the case at the outside of the door, has a bit or dog 30, which is operative on the main retracting lever 20, to retract the latch bolt, 5 but inoperative on the detent lever 25, to retract the latch bolt. To this end, the bit 30 is adapted to engage the free end 31 of a lever 32, pivoted in the case at 33, which free end 31 loosely rests on, and is supported by, 10 a lateral projection 34 on the lever 20. The parts are so arranged that when the bit 30 is turned in an anti-clockwise direction, with respect to Fig. 1, it will be unable to contact with the projection 24^a of lever 25, but will, 15 on the other hand, depress the lever 32 and actuate the lever 20 to retract the latch bolt without moving the lever 25 to any appreciable extent, as shown in Fig. 2. I have not considered it necessary to illustrate the pin 20 tumblers with which the cylinder locks 28 and 29 are provided, as this feature is well understood in the art.

The arm 24 of the lever 25 is made of special shape so that as said arm is actuated 25 by the bit of the inside cylinder lock 28, it may operate to hold the latch bolt in its retracted position. To this end, the edge portion of the arm 24, coacting with the projection 23 of the latch bolt lever, is formed 30 with a shoulder 39, having inclined edges 40, 41, directed at an angle to each other, to create a pointed projection as shown. As the latch bolt is retracted by the lever 25, the edge 40 of said shoulder or projection bears 35 against the projection 23, as the arm 24 moves toward the right with respect to Fig. 1. As the movement of the arm 24 continues, the shoulder 39 and projection 23 move relatively to each other in such a manner that as soon as the latch bolt has been 40 fully retracted, the projection 23 on the latch bolt lever passes the apex of the shoulder 39, and snaps into position against the edge 41 of said shoulder, whereby the lever 45 25 and the latch bolt 12 are locked in retracted position. In order to increase the security with which the latch bolt is held in this position, the detent lever 25 is provided with a rearwardly directed extension 42, 50 which, as the projection 23 passes from one side to the other of the shoulder 39, snaps into position in front of the crosshead 15 and engages said crosshead frictionally, as shown in Figs. 3 and 4. In this manner, the 55 latch bolt is held securely in retracted position, and it will remain in such position until the bit 27 is rotated in a direction opposite to that first indicated, in order to cause the abutment of the bit 27 against the 60 opposite side of the projection 24^a and the release of the lever 25, whereupon the parts will be restored by the latch bolt spring to the initial position.

When the latch bolt has been locked in 65 retracted position by the detent lever 25, it

will, preferably, be releasable by a key inserted at the outside of the door, as well as by a key inserted at the inside. The actuation of the lever 25 by the bit 30, as the latter is moved in an anti-clockwise direction 70 with respect to Fig. 1, is prevented by the means already described, but there are no means shown for preventing the release of the lever 25 by contact of the bit 30 with the projection 24^a, as said bit is moved in a 75 clockwise direction with respect to Fig. 3. Preferably, the inside and outside cylinder locks 28 and 29, respectively, will be operable by different keys, such as the keys 45 and 46 respectively, shown in Fig. 7. The key 45 80 may be termed the janitor's key, because in operating the cylinder lock 28 from the inside of the door, it will retract the latch bolt and stop it back in the case. The key 46 may be termed the teacher's key, because 85 when inserted in the outside cylinder lock 29, it will retract the latch bolt without, however, being operative to stop it back in the case. By the construction described, the actuation of the outside key in opening the 90 door for entrance cannot alter the normally locked condition of the door when the same is closed. When it is desired to stop back the latch, the janitor may readily do so by insertion of his key at the inside without 95 necessitating the opening of the door. Moreover, when the teacher's key will not operate the inside cylinder lock, as in the form illustrated, manipulation of the detent mechanism for the latch bolt is confined to the 100 janitor alone, which is desirable in some cases, but this is not an essential feature in all aspects of the invention. In the form illustrated the manually operable latch reTRACTING mechanism 16, 17, at the inside of 105 the door, is similar in its function to the outside cylinder lock in so far as it is incapable of operating the detent lever to stop back the latch bolt.

In the particular form shown, the latch bolt is dogged automatically on the closing of the door by means of a dogging lever 47 acted on by a spring 48 in such a manner that the head of such lever tends to lie in the path of the latch bolt so as to block the 110 incursion of the same. The lever 47 is held out of blocking position with respect to the latch bolt by a projecting controller bolt 49 which is forced in by contact with the strike 115 so as to cause the bolt to be dogged by the lever automatically on the closing of the door. In opening the door, a projection 50 on lever 20 engages a shoulder 51 on the tail of lever 47 in such a manner as to swing the lever out of the path of the bolt head in the 120 usual manner. In order to move the dogging lever out of the path of the bolt when the latter is to be retracted by the manual reTRACTING means at the inside of the door, the lever 16 acts on the lower extremity of 125

the lever 20 in a manner well understood in the art, so that said lever is swung on its pivot when the bolt is to be retracted by the manual retracting means, as well as when it 5 is to be retracted by the key operated means, so that the projection 50 on the lever 20 will throw off the dogging lever 47 and permit the latch bolt to be freely retracted. These features in themselves are old in the art, 10 but it will be apparent that by the construction described, the latch bolt may be retracted by the manual retracting means independently of the detent mechanism, and that thereafter the detent mechanism may be 15 moved by the rollback 27 to a position to dog the bolt in the retracted position. In other words, while the bolt is held back by the depression of the thumb piece, it may be dogged in retracted position by one of the 20 keys but not by another key, said first key operating the detent lever independently of the retracting mechanism. While the engagement of shoulder 39 on the detent lever with the pin or projection 23 on the retracting lever 20 is of importance, where it is 25 desired to move the latch bolt back and to dog it back in the case on the same movement of the key, the detent lever may, as described, be operated quite independently of 30 the retracting lever merely for the purpose of dogging the bolt in the retracted position after the bolt has been retracted by other means.

Of course, the various new functions 35 ascribed to the lock adapt it to buildings other than schoolhouses, and the invention has, in fact, quite a wide range of utility. The foregoing description is necessarily a detailed one, in so far as it concerns the 40 particular embodiment selected for illustration and description, but I desire to have it distinctly understood that numerous modifications may be made within the scope of the invention as defined in the claims. For 45 example, it is not essential in all aspects of the invention that the two keys having the two different functions be operative from opposite sides of the door respectively.

I do not claim herein the specific means 50 for retracting the latch bolt from one side of the door by means of a key acting on a detent member, nor do I claim means for retracting and holding retracted the member which controls the guarding or deadlocking 55 member for the latch bolt, or other features claimed in the companion application, Serial No. 710,570, above identified.

What I claim is:

1. In a lock, a latch bolt, a retracting 60 member therefor, a member for dogging the bolt in retracted position, said dogging member being adapted to operate said retracting member but the latter being operable independently, means for operating one

of said members from one side of the door, 65 and means for operating the other member from the other side of the door; substantially as described.

2. In a lock, a latch bolt, a member for dogging the bolt in retracted position, a bolt 70 retracting member, said dogging member being adapted to operate said bolt retracting member, but the latter being operable independently, and a lock mechanism having a dog to operate one of said members, and 75 another dog to operate the other member; substantially as described.

3. In a lock, a latch bolt, means including a cylinder lock at one side of the door for retracting said bolt and holding it in retracted 80 position, and means including a cylinder lock at the opposite side of the door to retract said bolt without holding it retracted; substantially as described.

4. In a lock, a latch bolt, inside and outside key mechanisms for retracting said latch bolt, and manually operable mechanism for retracting said bolt from the inside of the door, said inside key mechanism being operative to hold the latch bolt in retracted position, and said outside key mechanism and said manually operable mechanism being inoperative to hold said bolt retracted; 85 substantially as described.

5. In a lock, a latch bolt, a retracting member therefor adapted for independent operation, a detent member for operating said retracting member, key actuated means for operating said retracting member independently from the outside of the door, and 100 key actuated means for operating said detent member from the inside of the door; substantially as described.

6. In a lock, a latch bolt, a retracting member therefor adapted for independent operation, a detent member adapted to operate said retracting member, a cylinder lock at one side of the door to operate said retracting member independently of said detent member, and means at the other side 110 of the door to operate said retracting member through said detent member; substantially as described.

7. In a lock, a latch bolt, a retracting member therefor adapted for independent operation, a detent member adapted to operate said retracting member, means including a cylinder lock at the outside of the door for operating said retracting member independently, and means operable from the inside of the door to actuate said members together; substantially as described.

8. In a lock, a latch bolt, a retracting lever therefor, a detent lever adapted to operate said retracting lever, means including a cylinder lock at one side of the door to operate said retracting lever independently, and means including a cylinder lock

at the opposite side of the door to operate said retracting lever through said detent lever; substantially as described.

9. In a lock, a latch bolt, a retracting lever therefor, a detent lever adapted to operate said retracting lever, a cylinder lock having a bit adapted to act directly on said detent lever, a cylinder lock at the opposite side of the case, and means to prevent the retraction of said latch bolt by contact of the bit of said last named cylinder lock with said detent lever, but to permit the operation of said retracting lever by said bit; substantially as described.

10. In a lock, a latch bolt, means for retracting the same from either side of the door, by means of a key, and means for holding said latch bolt in retracted position when it is retracted from one side of the door, said latch bolt being releasable, when held in retracted position, by actuation of a key at either side of the door; substantially as described.

11. In a lock, a latch bolt, manual retracting means therefor at one side of the door, and separate key operated devices at opposite sides of the door for retracting said latch bolt, one of said key operated devices being operative to hold the latch bolt in retracted position, the latch bolt when so held being releasable by either of said key operated devices, but unreleasable by said manual retracting means; substantially as described.

12. In a lock, a latch bolt, key operated means at one side of the door for retracting the latch bolt as the key is turned in one direction, and for locking said bolt in retracted position as rotation of said key in the same direction is continued, and key mechanism at the opposite side of the door operative to retract said bolt, but inoperative to hold it retracted; substantially as described.

13. In a lock, a latch bolt, a plurality of keys, and mechanism operative by one of said keys to retract the latch bolt and hold it retracted, and operative in part by another of said keys to retract said bolt without holding it retracted; substantially as described.

14. In a lock, a latch bolt, retracting mechanism for dogging the bolt in retracted position, detent mechanism therefor, a key operative on both of said mechanisms, and another key operative on said retracting mechanism alone; substantially as described.

15. In a lock, a latch bolt, means to retract and stop back the same, a janitor's key operative on said means, to retract the latch bolt and hold it retracted, and a teacher's key operative on the retracting means to retract the bolt, but inoperative to hold it retracted; substantially as described.

16. In a lock, a latch bolt, a retracting member therefor, a detent member for dog-

ging the bolt in retracted position, a key to operate both of said members, and a key to operate the retracting member alone; substantially as described.

17. In a lock, a latch bolt, a retracting lever therefor, a detent lever adapted to operate the retracting lever, a key to operate said levers together, and another key to operate the retracting lever independently; substantially as described.

18. In a lock, the combination of a latch bolt, a cylinder lock at the inside of the door, a dog or bit on said cylinder lock, a lever pivoted to the case and operable by said dog or bit to dog the bolt in retracted position, and a second cylinder lock at the outside of the door to retract the latch bolt without operating said dogging lever; substantially as described.

19. In a lock, the combination of a latch bolt, a pin tumbler lock mechanism, a plurality of keys adapted to said pin tumbler lock mechanism, and mechanism operable by one of said keys to retract the latch bolt and dog it in retracted position, said mechanism being operative by another of said keys to the extent of retracting the bolt, but inoperative by said second key to dog the bolt in retracted position; substantially as described.

20. In a lock, a latch bolt, retracting mechanism therefor, detent mechanism for dogging the bolt in retracted position, pin tumbler lock mechanism, a key operative on said retracting mechanism and on said detent mechanism, through said pin tumbler lock mechanism, and another key operative on said retracting mechanism alone, through said pin tumbler lock mechanism; substantially as described.

21. In a lock, a latch bolt, a member for dogging said bolt in retracted position, a member for retracting said bolt, said dogging member being adapted to operate said retracting member, but the latter being operable independently, a cylinder lock at one side of the door having a dog to operate the retracting member independently, and a cylinder lock at the opposite side of the door having a dog to operate said retracting member by means of the dogging member; substantially as described.

22. In a lock, a latch bolt, a retracting lever therefor, a detent lever adapted to operate the retracting lever, and a pin tumbler lock mechanism having a dog to operate the detent lever, and another dog to operate the retracting lever independently; substantially as described.

23. In a lock, a latch bolt, retracting mechanism therefor, detent mechanism for dogging the bolt in retracted position, a pin tumbler lock mechanism having two dogs, a key operative on one of said dogs to retract the bolt, and dog it in retracted posi-

tion, and a key operative on the other dog to retract the bolt without dogging it in retracted position; substantially as described.

24. In a lock, a latch bolt, two keys, means for retracting said bolt by either key, and means for dogging said bolt in retracted position by one key, said last means being inoperative by the other key, said bolt being releasable from dogged position by either of said keys; substantially as described.

25. In a lock, a latch bolt, retracting mechanism therefor, detent mechanism for dogging the bolt in retracted position, pin tumbler lock mechanism, a key operative on said retracting mechanism and on said detent mechanism through said pin tumbler lock mechanism, and another key operative on said retracting mechanism alone through said pin tumbler lock mechanism, said latch bolt being releasable from its dogged position by either of said keys; substantially as described.

26. In a lock, a latch bolt, a retracting member therefor, a dogging member for said bolt, said retracting member operable independently or through said dogging member, a key for operating said retracting member independently, and a key for operating both of said members together; substantially as described.

27. In a lock, a latch bolt, two keys, means for retracting said bolt by either key, and means for dogging said bolt in retracted position by one key, said last means being inoperative by the other key; substantially as described.

28. In a lock, the combination of a latch bolt, retracting mechanism therefor, mechanism for dogging said bolt in retracted position, a key operative on the retracting mechanism but inoperative on the dogging mechanism, and another key operative on both of said mechanisms; substantially as described.

29. In a lock, a latch bolt, retracting mechanism therefor, detent mechanism for dogging the bolt in retracted position, pin tumbler lock mechanism, a key operative on said pin tumbler lock mechanism to dog the bolt in retracted position, and another key operative on said pin tumbler lock mechanism to retract the bolt, said second key inoperative to dog the bolt in retracted position; substantially as described.

30. In a lock, a latch bolt, retracting mechanism therefor, detent mechanism for dogging the bolt in retracted position, pin tumbler lock mechanism, a key operative on said retracting mechanism and on said detent mechanism through said pin tumbler lock mechanism, and another key operative on said retracting mechanism but not on said detent mechanism through said pin tumbler lock mechanism; substantially as described.

31. In a lock, the combination of a latch bolt, pin tumbler lock mechanism having two rollbacks, means actuated by one of said rollbacks to retract the bolt, and means actuated by the other rollback to dog the bolt in retracted position, said first rollback inoperative to dog the bolt; substantially as described.

32. In a lock, the combination of a latch bolt, manual retracting means therefor, a pin tumbler lock mechanism having two rollbacks, means actuated by one of said rollbacks to retract the bolt, and means operated by the other rollback to dog the bolt in retracted position when the same has been retracted by said manual retracting means, said first rollback inoperative to dog the bolt; substantially as described.

In witness whereof I have hereunto set my hand on the 29th day of November, 1913.

ALBERT A. PAGE.
